Application February 23, 1935, Serial No. 7,768

19 Claims. (Cl. 82—15)

This invention relates to a machine for shaping or turning internal combustion motor pistons and the like.

The main objects of this invention are to provide an improved machine for turning pistons and the like to an elliptical cross-sectional shape; to provide a machine for turning a piston or like work piece to slightly helical shape in an axial direction; to provide a machine for turning a piston having an elliptical shape at any cross-section normal to the longitudinal axis of the piston but with the major axes of such elliptical cross-section shifting to different rotational positions along the piston, and to provide a machine 10 of this character which can be readily adjusted to vary the shape of the piston or the like being turned.

An illustrative embodiment of this invention is shown in the accompanying drawings, in which Fig. 1 is a view in perspective of the improved machine.

Fig. 2 is an enlarged fragmentary transverse vertical sectional view of the same taken on the line 2—2 of Fig. 1, looking in the direction indicated.

Fig. 3 is a view in elevation of the cutting tool spindle and bracket therefor as viewed from the near side of the machine illustrated in Fig. 1.

Fig. 4 is a view in elevation of the same as seen from the right hand end of Fig. 3.

Fig. 5 is a longitudinal vertical sectional view of the same, showing the means for raising the rear end of the spindle during the cutting or turning operation, taken on the line 5—5 of Fig. 6.

Fig. 6 is a view of the same, partly in top plan and partly in horizontal section, showing the relation of the spindle to the piston or like work piece being turned.

Fig. 7 is a view in elevation as seen from the left hand end of Fig. 6.

Fig. 8 is an enlarged view, partly in top plan and partly in horizontal section of the forward end of the spindle and a modified form of work holding device with the work piece positioned thereon, showing the relation of the axis of rotation of the spindle to the axis of the piston being turned.

Fig. 9 is a sectional view taken on the line 9—9 of Fig. 8, looking in the direction indicated.

Fig. 10 is a top plan view of a two spindle machine in which both spindles are belt driven by a single motor.

Fig. 11 is a view in elevation of the left hand end of the machine shown in Fig. 10.

Fig. 12 is a top plan view of a machine having three spindles belt driven by two different motors and illustrating the offset or echelon positioning of the spindles.

Fig. 13 is a view in elevation of the skirt end 5 of a piston showing the elliptical shape thereof.

Fig. 14 is a view in side elevation of the same, showing the tapering of the same from the skirt toward the head.

Fig. 15 is a side elevation of the piston shown 10 in Fig. 14, the view being taken with the piston rotated 90° about its longitudinal axis with reference to the position depicted in Fig. 14.

Fig. 16 is an enlarged side elevation of the work holding fixture shown in Fig. 1, a piston being 15 shown mounted thereon.

Fig. 17 is an enlarged vertical section taken in a plane through the piston axis in Fig. 16.

Fig. 18 is a further enlarged end elevation of work piece engaging parts shown in Fig. 17, and 20

Fig. 19 is a view similar to Fig. 17 of a modified form of work piece holding and aligning means.

In the construction shown in the drawings, the machine in general comprises a base support 15 25 of substantially rectangular shape and having a reciprocating work holding table 16 slidably mounted in ways on the top thereof. A work holding fixture or support 17 is mounted on the table 16 for carrying a piston 18 or like piece of 30 work toward and away from the cutting tool of the spindle. The base 15 has an inverted U-shaped bridge 20 mounted on laterally projecting shoulders 21 and 22 integrally formed thereon and which supports a horizontally disposed motor driven spindle assembly generally designated 35 23 in Fig. 1 of the drawings.

Referring to Figs. 2 to 7, the spindle assembly comprises a frame 24 secured to the top of the bridge, 20 by vertically disposed bolts 25, the 40 heads of which engage in inverted T-slots 26 formed in the top surface of the bridge 20. A centering disk 27 is attached to the underside of the frame 24 at the middle thereof by cap screw 28 and is received in an aperture 29 formed in the top surface of the bridge 20. The frame 24 45 may be pivotally swung horizontally about the disk 27 for positioning the frame at different angles with respect to the bridge.

The front end of the frame 24 is provided with 50 an integrally formed depending lug 30 which is received between the inner ends of axially aligned, opposed adjusting screws 31 and 32 which are threaded through lugs or bosses 33 and 34, respectively, rigid on the bridge 20. The rear end 55

of the frame 24 is also provided with laterally spaced depending lugs 35 and 36 which are positioned between axially aligned opposed adjusting screws 37 and 38 which are threaded through lugs or bosses 39 and 40 respectively, which are rigidly attached to the bridge 20. All of the adjusting screws are provided with Jamb nuts 41 for securing the screws in position when adjusted.

The frame 24 is formed with a relatively flat bottom portion with upstanding sides and at the front end thereof the sides curve toward each other to form an inverted U-shaped portion 42 which imparts rigidity to that end of the frame, the base of the frame being cut away at this point and the sides continued forward in advance of the portion 42 to form a pair of spaced parallel axially aligned bearing heads 43 and 44.

A generally tubular shaped spindle bracket 45 is pivotally mounted at its forward end between the bearing heads 43 and 44 by trunnions 46 and 47 which pass through the bearing heads and through similar bearing heads 48 and 49 formed on the spindle bracket. The bracket 45, adjacent its rear end, is provided with laterally projecting screw studs 50 and 51 which extend into vertically disposed slots 52 and 53 respectively formed in the upstanding sides of the frame 24. The slots 52 and 53 are formed at the lower end of vertically disposed bores formed in the thickened side walls and in which are contained helical compression springs 54 and 55 which bear between the studs 50 and 51 at their lower ends so that the rear end of the bracket is yieldingly urged downwardly at all times.

Means are provided for supporting the rear end of the bracket 45 against the action of the compression springs and comprise a vertically disposed post 58 slidably mounted in a sleeve bracket 59 which is rigidly attached to the bridge 20. The upper end of the post 58 is axially bored and threaded to receive an adjusting screw 60, the head of which is recessed to receive a ball bearing 61, which provides rolling contact with the side wall surfaces 62 of an inverted V-shaped groove formed in a bearing block 63 which is rigidly attached to the spindle bracket 45. Rotative movement of the post 58 is limited by the inner projecting end of a screw 64 which is received in an axially disposed slot 65 formed in the post 58, as shown in Fig. 5.

The lower end of the post 58 is bifurcated to form a pair of spaced parallel arms 66 and 67, between which is journaled a roller or wheel 68 on a pin 69. The wheel or roller 68 rests upon the top surface of a cam block 70 which is rigidly secured to the table 16 by screws 71, 72 and 73, the latter two of which pass through angle shaped clips 74 and 75 respectively. The vertical arm of each clip rests on the top of the table 16 and the horizontal arm of each overlaps the extended marginal edges 76 and 77 respectively, of the cam block 70. The top surface of the cam plate 70 is sloped as shown at 70A, so as to move the post 58 upwardly and thereby raise the rear end of the spindle bracket to the position shown in dotted outline (Fig. 5) when the table 16 moves to the left with respect to the stationary bridge 20.

The spindle bracket 45 is provided with spaced axially aligned spindle bodies 78 and 79 rigidly retained therein by clamping bolts 78A and 79A, respectively. The bodies 78 and 79 carry special ball bearing assemblies 80 in which is journaled a spindle shaft 81. The field 82 and armature 83 of an electric motor are positioned between

the spindle bodies 78 and 79 within the bracket 45, the armature 83 being carried on and rigidly attached to the spindle shaft 81 for driving the same while the field 82 is rigidly attached to the bracket 45.

The rear end of the spindle shaft 81 projects from the bracket 45 sufficiently to receive a brake drum 84 which is keyed thereto in the usual manner. The forward end of the spindle shaft 81 is provided with an axially disposed tapered socket 85 for receiving the shank of a cup-shaped cutting tool carrying cage 86, the rim 87 of which is drilled in a radial direction to receive a cutting tool 88 which is adjusted or positioned in a radial direction by a threaded plug 89 which abuts against the base end of the cutting tool. The cutter 88 is also held by the inner end of the screw 90 which is threaded into rim 87 of the tool holder 86 in a direction substantially at right angles to the axis of the cutting tool 88. The tip or point of the cutting tool 88 is so positioned and arranged as to rotate in a plane which contains the axis of the trunnions 46 and 47.

In the modified form illustrated in Figs. 8 and 9, the work-holding fixture comprises a work-holding head 91 having clamping plates 92 and 93 bolted to the front face thereof. An axially disposed supporting shaft 94 extends from the rear of the head 91 which is journaled in spaced axialy aligned bearings 95 and 96 formed in the supports 97 and 98 respectively, and which are formed on the top surface of a base plate 99.

The underside of the base plate 99 is supported on the table 16, which slides on the ways 101 of the base 15. The shaft 94, at a point between the spaced bearings 95 and 96, is provided with a radially extending arm 103, the outer free end of which is pivoted to one end of a link 104, the other end of which is pivoted to one end of a horizontally slidably push bar 105. The push bar 105 is slidably mounted in an upstanding supporting bracket 106 formed on the top surface of the base plate 99. The end thereof opposite to the pivoted link 104 is bifurcated to receive a journaled roller 107 which rides against a cam surface 108 formed at the upper end of a bracket arm 109, the lower end of which is rigidly secured to the stationary supporting base 15 by bolts 110.

A helical tension spring 111 has one end attached to the upstanding bracket 106 and the other end thereof attached to a depending hook 112 formed at the extremity of the arm 103 for normally maintaining the roller 107 in contact with the cam surface 108.

In the operation of this device, the spindle bracket supporting frame 24 is pivotally swung about the centering disk 27 and accurately positioned by means of the adjusting screws 31, 32, 37 and 38 so that the plane of rotation of the cutting tool 88 will be at a predetermined angle with respect to a plane normal to the axis of the piston 19 or other work piece which may be placed on the work holding fixture 17.

The clamping bolts 25 are then tightened so as to rigidly hold the spindle supporting frame in such position. A work holding fixture is then moved toward the spindle along the axis line 113, as shown in Figs. 6 and 8, so that the cutting tool, as it engages the end of the piston 19 will, when viewed from a direction normal to the axis of the piston, describe an ellipse, thereby cutting away the material shown by dotted lines 114 in Fig. 13, to form the skirt end of the piston to elliptical shape.

As the work holding fixture continues to advance toward the spindle, the cam surface 10A will, by engagement with the roller 68 and through the post 88, ball 61 and bearing block 5 63, raise the rear end of the spindle bracket, thereby changing or varying the plane of rotation of the cutting tool 88 in a direction at right angles to that secured by angular adjustment of the spindle supporting frame 24.

10 This movement of the rear end of the spindle causes the bracket to pivot on the trunnions 46 and 47, the axis of which trunnions intercept the center of the plane of rotation of the cutting tool 88. Thus the cutting tool 88 will also describe a path of elliptic shape when viewed in the direction of the axis of the spindle and in a direction in a horizontal plane parallel to the axis of the piston, the combination of the two movements producing a piston or other work 15 20 piece elliptical in shape when viewed as in Fig. 13, and generally tapered shape, when viewed as in Fig. 14, by reason of the removal of the material shown by the dotted lines 115 in Fig. 14 and by the dotted lines 114 in Fig. 13.

25 The shape of the piston is, however, not that of a true frusto-cone, but is elliptical at any section taken normal to the axis of the piston. The major axes of such elliptical sections, however, shift in a rotational direction by an amount proportional to the angle through which the spindle axis is swung in a vertical plane about the pivots 46 and 47. Thus the piston, when fitted to a true cylindrical bore has an outside bearing land 116 on each of the two opposite sides 30 35 thereof, which describe upon the surface of the said piston a helix. These lands 116 are, therefore, not truly axially disposed but, due to the way in which they are cut, they are inclined or helical with respect to the axis of the piston, as indicated in Figs. 14 and 15, the angle of the helix with respect to an axial direction being determined by the angle of the cam surface 10A which raises the rear end of the spindle.

40 In the event this helical angle of the lands is desired to be decreased, eliminated, or increased, use is made of the modified form of fixture holding head shown in Figs. 8 and 9, the cam surface 108 of which can be arranged to either decrease, increase or entirely eliminate the helix angle of the bearing lands. The comparatively narrow helical land provides a wide bearing contact in the cylinder in which the piston is disposed and eliminates localized wear on the cylinder walls which would occur if the land were axially disposed. The effective support of the piston in the cylinder is thereby circumferentially increased, while the advantages of a narrow bearing which allows room for expansion of the piston is retained.

50 55 60 In the form of the invention shown in Figs. 10 and 11, two belt driven spindle units 120 and 121 are ganged together on a common base and driven by a single motor 122 which is rigidly bolted to the outer side of the frame or spindle unit 121, a double belt pulley 123 being provided on the armature shaft of the motor for driving two belts 124 and 125 which pass around pulley wheels 126 and 127 respectively, which are keyed to the protruding ends of the spindle shafts 128 and 129 respectively.

65 70 The spindle units 120 and 121 are in offset relation to each other an amount equal to the angle at which the spindle units are set with respect to the axis of the piston being turned, so that the cutters of the two spindle units will

engage and simultaneously begin cutting the ends of the pistons, the direction of movement of the pistons or other work being along the lines 130.

75 As the pistons or other work are moved into engagement with the cutting tools, the rear ends of the spindle brackets are cammed upwardly against the action of helical compression springs 132 in the same manner as in the preferred form of the device shown in the preceding figures.

10 In the embodiment of the invention shown in Fig. 12, three spindles and spindle bodies 140, 141, 142 are mounted in a single bracket 143 which is pivoted at 144 and 145 to the forwardly projecting bearings 146 and 147 of a frame 148. 15 It will be noted that the planes of the cutting tools 149, 150 and 151 are at a slight angle with respect to the axis formed by the pivot mountings 144 and 145, instead of the axis being in the plane of rotation of the tools as in the preceding forms, the arrangement being such that the axis of the tilting mountings passes through the centers of the paths described by the three cutting tools.

20 25 The spindle shafts journaled in the bodies 140 and 141 protrude from the rear end thereof and are provided with belt pulley wheels to receive drive belts 152 from the motor 153. The spindle shaft of the body 142 is similarly driven from a single motor 154 through belts 155.

30 35 Reference may now be had to Figs. 16, 17 and 18, which illustrate more in detail the construction of the work holding fixture 17. The upper portion of the fixture 17 is provided with an enlarged cylindrical boss portion 160 provided with a horizontally disposed bore 161 bushed at 162 and in which is received a horizontally reciprocable plunger 163. The inner or left hand end of plunger 163 is provided with an enlarged head portion 164 in which is formed a partially spherical seating surface 165 cooperable with a correspondingly shaped bearing surface 166 of a swivelled work engaging element 168. Spaced lugs 167 are provided upon the work engaging face of the swivelled element 168. A plurality of pins 170 are fixed to the swivelled element 168 and extend to the right therefrom, as indicated in Fig. 17, into suitable borings 171 provided in the enlarged head portion 164 to limit rotation of the swivelled element 168 relative to the plunger 163 40 45 50 and also to limit swivelling movement of the element 168 with reference to the plunger 163 and head portion 164 thereof. The swivelled element 168 is provided with a step bore 173 through which projects, in spaced relation from the walls thereof, a stud bolt 174. A spring 175 is arranged in compressed condition between the head of the stud bolt 174 and a radially inwardly directed flange 176 provided on the swivelled element 168 so as yieldably to urge the swivelled element 168 55 60 65 into contact with the enlarged head portion 164 of the plunger 163. This urges the spherical surface bearing surfaces 165 and 166 into close contact at all times to prevent admission of dirt or other foreign matter between the swivelled element and the head portion 164. The plunger 163, its enlarged head portion 164 and the swivelled element 168 provide a movable clamping element for retaining the piston 19 secured to the fixture 17.

70 75 The head portion 164 is provided with a recess on adapter 180 opening to the left from the head portion and shaped so as to receive the peripheral surface of the work piece at the right hand end thereof so as to align the work piece 19 with its

- axis in a predetermined position with reference to the fixture 17. A stationary clamping element 181 provided with a radially inwardly directed flange 182 is secured to the fixture 17.
- 5 The flange 182 is of U-shaped form, as indicated in Fig. 18, and is adapted to be received within a ring groove 183 of piston 19 or in a similar peripheral groove within the work piece to be turned.
- 10 The plunger 163 may be actuated toward and away from the stationary clamping flange 182 by means of the manually operated crank 184, illustrated in Fig. 1. The operating connection between the manual actuated crank 184 and the plunger 163 may be in the form of a screw, hydraulic means, or any other desired type of actuating means commonly employed in the art. The specific actuating means is not illustrated in the present instance, since the particular type 15 of actuating means used forms no part of the present invention.
- In mounting a piston 19, or similar work piece, upon the fixture 17, the work piece is slid downwardly with the flange 182 of the stationary clamp 181 disposed within the peripheral ring groove 183 of the piston 19 or similar work piece and the swiveled clamping element 168 brought into engagement with the adjacent end face of the work piece. The spaced work engaging lugs 20 167 upon the swiveled clamping element 168 upon movement of the plunger 163 in the direction indicated by the arrow 185 of Fig. 17 bring the head end wall of the groove 183 into firm engagement with the flange 182 to secure the desired alignment of the piston 19 with reference to the fixture 17. The recessed adapter 180 upon the enlarged head end portion 164 of plunger 163 of the movable clamping element maintains the longitudinal axis of the piston 19, or similar work piece, in a desired predetermined position with reference to the fixture 17. The element 168 is free to swivel relative to the enlarged head portion 164 a sufficient amount so that the surface of the work contacting the lugs 167 does not have to be accurately machined or aligned with reference to the groove face 183. The piston 19, or similar work piece is held clamped to the fixture 17 in the position indicated in Figs. 16 and 17, while the work piece is turned to the desired shape and then may be removed from the fixture 40 by retracting the plunger 163 in a direction opposite to that indicated by the arrow 185 in Fig. 17. The work piece may then be lifted in a vertical direction out of the clamping means secured to the fixture 17.
- 45 Reference may now be had to Fig. 19 in which a slightly modified form of movable clamping member and adapter is employed. In this embodiment a fixed clamping member 181 is secured to the fixture 17 and provided with a substantially U-shaped flange 182 adapted to engage a ring groove or similar peripheral groove 183 of the work piece. A reciprocable plunger 263 is mounted within a bushing 162 pressed within the bore 161 of the upper enlarged portion 160 of the fixture 17. An enlarged head portion 264 is provided on the plunger 263 in much the same manner as in the embodiment previously described and a swiveled element 268 and the head portion 264 are provided with partially spherical bearing portions as before. Swiveling movement of the element 268 with reference to the enlarged head portion 264 is limited by a plurality of stud screws 270, three in number being preferably employed, and arranged in the relation indicated

5 by the aligning pins 170 of Fig. 18. Springs 269 are arranged in compressed relation between the head 270 and flange 276 provided on the swiveled element 268 for resiliently urging the swiveled element into engagement with the enlarged head portion 264 to prevent admission of dirt or foreign matter between such enlarged head portion and the swiveled element 268. Spaced work engaging lugs 267 are provided on the swiveled element 268, as before.

10 The adapter for aligning the longitudinal axis of the work piece or piston 19 in this embodiment takes the form of a reciprocable center 280 mounted within a bore 290 provided at the inner or left hand end of the plunger 263. A spring 291 is arranged in compressed condition between the bottom of the bore 290 and the outer or right hand end of the reciprocable center 280 for forcing the latter outwardly to project a point 292 within a suitable axially arranged opening 294 15 within the work piece or piston 19. An axially arranged groove 295 is provided in the periphery of the reciprocable center 280 and a stud screw 296 cooperates therewith for preventing removal of the center 280 from the plunger 263.

20 The operation of this work holding means is essentially the same as that described with reference to Figs. 16 to 18, inclusive, with the exception of the fact that the spring urged center 280 is employed for maintaining the longitudinal 25 axis of the work piece 19 in the predetermined position with reference to the fixture 17 instead of an adapter such as 180 employed in the embodiment shown in Figs. 17 and 18 to engage the peripheral margin of the head end of the work piece.

25 Although several different embodiments of this invention have been herein shown and described, it will be understood that numerous details of the constructions shown may be altered or omitted without departing from the spirit of this 30 invention as defined by the following claims.

35 We claim:

1. In a machine for shaping or turning an approximately cylindrical piece of work, a support, a work holding device on said support, a device on 40 said support having a cutting tool journaled to rotate in a plane about an axis so as to circumscribe a generally circular area, means for moving one of said devices toward the other for engaging the work and cutting tool, said cutting 45 tool's axis of rotation being at an angle to the direction of relative movement of said devices and intersecting with the longitudinal axis of the work piece in such plane.

50 2. In a machine for shaping or turning an approximately cylindrical piece of work, a support, a work holding device on said support, a spindle device on said support, a cutting tool rotated by said spindle in an orbit about the axis of the spindle so as to circumscribe a generally circular area, means for moving one of said devices toward the other for engaging the work and cutting tool, the plane of orbital movement of said cutting tool being at an angle to a plane normal to the direction of relative movement of said 55 devices and the center of said area coinciding with the longitudinal axis of the work piece.

3. In a machine for shaping or turning a piece 60 of work, a support, a work holding device on said support, a device on said support having a cutting tool journaled to rotate in a plane about an axis, means for moving one of said devices toward the other for engaging the work and cutting tool, said cutting tool's axis of rotation being at an angle to the direction of relative movement of said de- 65

vices and means for changing the plane of rotation of said cutting tool during the period of engagement with the work.

4. In a machine for shaping or turning a piece of work, a support, a work holding device on said support, a device on said support having a cutting tool journaled to rotate in a plane about an axis, means for moving one of said devices toward the other for engaging the work and cutting tool, said cutting tool's axis of rotation being at an angle to the direction of relative movement of said devices, and means for progressively changing the plane of rotation of said cutting tool during the period of engagement with the work.

15. 5. In a machine for shaping or turning a piece of work, a support, a work holding device on said support, a device on said support having a cutting tool journaled to rotate in a plane about an axis, means for moving one of said devices toward the other for engaging the work and cutting tool, said cutting tool's axis of rotation being at an angle to the direction of relative movement of said devices, and means for moving the axis of rotation of said cutting tool at an angle to the direction of relative movement of said devices during such relative movement but in a direction different from the first mentioned angular divergence.

30. 6. In a machine for shaping or turning a piece of work, a support, a work holding device on said support, a device on said support having a cutting tool journaled to rotate in a plane about an axis, means for moving one of said devices toward the other for engaging the work and cutting tool, said cutting tool's axis of rotation being at an angle to the direction of relative movement of said devices, and means for moving the axis of rotation of said cutting tool at an angle to the direction of relative movement of said devices during such relative movement but in a direction substantially at right angles to the first mentioned angular divergence.

45. 7. In a machine for shaping or turning a piece of work, a support, a work holding device on said support, a device on said support having a cutting tool journaled to rotate in a plane about an axis, means for moving one of said devices toward the other for engaging the work and cutting tool, said cutting tool's axis of rotation being at an angle to the direction of relative movement of said devices, and means for moving the axis of rotation of said cutting tool at an angle to the direction of relative movement of said devices during such relative movement but in a direction different from the first mentioned angular divergence, and means for imparting limited rotation to the work being shaped during the shaping operation.

55. 8. In a machine for shaping or turning a piece of work, a support, a work holding device on said support, a device on said support having a cutting tool journaled to rotate in a plane about an axis, means for moving one of said devices toward the other for engaging the work and cutting tool, said cutting tool's axis of rotation being at an angle to the direction of relative movement of said devices, and means for moving the axis of rotation of said cutting tool at an angle to the direction of relative movement of said devices during such relative movement but in a direction different from the first mentioned angular divergence, and means for imparting limited rotation to the work being shaped on an axis parallel to the direction of relative movement of said device, during such relative movement.

9. In a machine for shaping or turning a piece of work, a support, a work holding device on said support, a spindle device pivoted to said support, a cutter rotated by said spindle in a plane containing the axis of said spindle pivot, means for moving one of said devices relative to the other for engaging the work and cutter and means for moving said spindle device on its pivot during such relative movement.

10. In a machine for shaping or turning a piece of work, a support, a work holding device on said support, a spindle device pivoted to said support, a cutter rotated by said spindle in a plane containing the axis of said spindle pivot, means for moving one of said devices relative to the other for engaging the work and cutter, the plane of rotation of said cutter being at an angle to a plane normal to the direction of such movement, and means for moving said spindle device on its pivot during such relative movement.

15. 11. In a machine for shaping or turning a piece of work, a support, a work holding device on said support, a spindle device pivoted to said support, a cutter rotated by said spindle in a plane containing the axis of said spindle pivot and perpendicular to the axis of rotation of said spindle, means for moving one of said devices relative to the other for engaging the work and cutter, the axis of said spindle being positioned at an angle to the direction of relative movement of said devices and in a plane containing the axis of said spindle pivot, and means for moving said spindle on its pivot during such relative movement.

20. 12. In a machine for shaping or turning a piece of work, a support, a work holding device on said support, a spindle device pivoted to said support, a cutter rotated by said spindle in a plane perpendicular to the axis of rotation of said spindle and containing the axis of said spindle pivot, means for moving one of said devices relative to the other for engaging the work and cutter and means for moving said spindle on its pivot during such relative movement.

25. 13. In a machine for shaping or turning a piece of work, a support, a work holding device on said support, a spindle device pivoted to said support, the axis of said pivot being perpendicular to the axis of rotation of said spindle, a cutter rotated by said spindle in a plane perpendicular to the axis of rotation of said spindle and containing the axis of said spindle pivot, means for moving one of said devices relative to the other for engaging the work and cutter and means for moving said spindle on its pivot during such relative movement.

30. 14. In a machine for shaping or turning a piece of work, a support, a work holding device on said support, a spindle device pivoted to said support, a cutting tool rotated by said spindle in a plane normal to the axis of rotation of said spindle, means for moving one of said devices relative to the other for engaging the work and cutting tool, the axis of rotation of said spindle being at an angle to the direction of relative movement of said devices and in a direction parallel to a plane containing the axis of rotation of said spindle and the axis of said pivot mounting.

35. 15. In a machine for shaping or turning a piece of work, a support, a work holding device on said support, a spindle device pivoted to said support, a cutting tool rotated by said spindle in a plane normal to the axis of rotation of said spindle, means for moving one of said devices relative to the other for engaging the work and

cutting tool, the axis of rotation of said spindle being at an angle to the direction of relative movement of said devices and in a direction parallel to a plane containing the axis of rotation of said spindle and the axis of said pivot mounting and means for moving said spindle device on its pivot during such relative movement.

16. In a machine tool, a base having a stationary support and a movable support thereon, a work holding fixture mounted on said movable support for supporting a generally cylindrical work piece with the longitudinal axis of said work piece disposed parallel to the direction of movement of said movable support, a single-point tool, a tool spindle mounted on said stationary support for rotating said single-point tool about the axis of said spindle, means for rotating said spindle, the longitudinal axis of said work piece and the axis of said spindle being disposed at an angle 10 and intersecting at the center of the path of tool rotation, and means for causing relative movement of said movable support with respect to the tool whereby said tool will generate an elliptical 20 surface of said work piece.
17. A machine for providing a work piece with an elliptical surface which comprises means for holding the work piece substantially against rotation, a single-point tool adapted to engage the work piece, means for rotating the tool, and means for advancing the tool and work piece 25 relative to each other with the path of relative

movement directed at an acute angle to the plane of tool rotation.

18. A machine for shaping a work piece initially of generally cylindrical shape to provide an elliptical surface, which comprises means for holding the work piece substantially against rotation, a single-point tool adapted to engage the work piece, means for rotating the tool, and means for relatively advancing the work piece and tool to cause the tool to engage the work piece 10 progressively along the latter with the longitudinal axis of the work piece progressively during such movement coinciding with the center of the area defined by rotation of the tool point, but with such axis directed at an acute angle to the 15 plane of tool rotation.

19. A machine for shaping a work piece initially of generally cylindrical shape to provide an elliptical surface, which comprises means for holding the work piece substantially against rotation, a single-point tool adapted to engage the work piece, means for rotating the tool, and means for advancing the work piece with respect to the tool to cause the latter to engage the work 20 progressively therealong, with the axis of the 25 work piece during such movement remaining unchanged in direction, coincident to the center of the area defined by the tool point rotation, and directed to an angle to the plane of tool rotation.
